UNITED STATES PATENT OFFICE.

FRANK. W. OFELDT, OF JERSEY CITY, NEW JERSEY, ASSIGNOR TO THE
MARINE VAPOR ENGINE COMPANY, OF SAME PLACE.

STEAM-WHISTLE.

SPECIFICATION forming part of Letters Patent No. 532,088, dated January 8, 1895.

Application filed December 23, 1893. Serial No. 494,590. (No model.)

To all whom it may concern.

Be it known that I, FRANK. W. OFELDT, of Jersey City, in the county of Hudson and State of New Jersey, have invented certain new and useful Improvements in Steam-Whistles; and I do hereby declare the following to be a full, clear, and exact description of the invention, such as will enable others skilled in the art to which it appertains to make and use the same.

My invention relates to an improvement in steam whistles, the object being to provide improved means for the generation and control of steam for use in blowing whistles; and it consists in a boiler adapted to receive water and have steam generated therein, a pipe leading out of this boiler, and means for heating the boiler whereby steam is generated in connection with a whistle to which the steam generated is applied.

It further consists in certain novel features of construction and combinations of parts, which will be hereinafter described, and pointed out in the claims.

My invention comprehends devices consisting of a cold water tank connected with a steam generator or boiler wherein the water circulates under an elastic pressure into the boiler through a suitable pipe, the boiler being provided with a whistle or alarm device, and the steam therein being adapted if the pressure becomes excessive to force itself by its own pressure backward toward the cold water tank and become condensed, whereby the apparatus is automatic in its action and absolutely safe in its operation.

In the accompanying drawings, Figure 1 is a view showing the entire apparatus connected together for operating the whistle, and Fig. 2 is an enlarged sectional view.

A represents a boiler it being located in some convenient heating chamber such as a retort B as shown where heat is generated by means of a burner C or it might be located in any other heating device or chamber suitable for the purpose, the object being to generate steam in the boiler. When a retort is employed such as the one shown a series of coils of pipes D, D, may be wound loosely around the boiler for generating vapor in the retort. This construction is more particularly de-

scribed and claimed in a separate application concurrently pending. It is merely alluded to here as the pipes D, D, have a tendency to assist in concentrating and radiating heat and in consequence add to the efficiency of the invention.

Immediately surrounding the boiler A is a steam pipe a which is in communication with one end of the boiler and is coiled around the latter from this end to the other, the purpose of this pipe a being to conduct the steam from the boiler to the whistle and at the same time to cause the steam in its passage through it to become superheated and dry. The coils of pipe a are not close together so that the heat from the burner is not shut off from the boiler A and the coils of pipe a each resting upon and surrounding the boiler, not only receive heat from the burner direct but also from the boiler itself so that the superheating is successfully accomplished.

The superheating coil or pipe may be omitted if desired, and the whistle connected directly with the boiler A, as in most cases the temperature of the boiler may be maintained sufficiently great to obviate the necessity of any special superheating of the steam.

The whistle itself is operated in the usual way and hence it requires no description, it simply being provided with a valve under the control of the engineer for the escape of steam.

Water is supplied to the boiler A from a tank E, the latter being refilled when occasion requires it. A condensing pipe e leads from the tank down through the water beneath the boat when the whistle is used on a boat or through some other condenser when used in any other place.

Air pump F is connected with the tank E and by means of it a suitable pressure of air is created in the tank to cause an automatic flow of water from the latter into the boiler A, so that the boiler is always supplied with an adequate amount of water for the generation of steam. In this way of course as soon as steam is blown off in blowing the whistle more water flows in at once to supply the boiler, and on the other hand any excessive pressure of steam in the boiler causes a back pressure upon the water in condensing pipe

e and in this manner the steam finds escape back through the condensing pipe where it is condensed and returned to the tank and also when heat is shut off the steam condensing in the boiler flows back into the condensing pipe.

If the tank E is made sufficiently large it might of itself act as the means for condensing the steam which may be forced backward from the boiler, though in the case of launches it is advisable to employ the condensing coil arranged upon the bottom of the boat.

Slight changes and variations might be made in the various details of the invention without departure from the spirit and scope of my invention and hence I do not wish to limit myself to the exact construction herein set forth, but,

Having fully described my invention, what I claim as new, and desire to secure by Letters Patent, is—

1. In a whistle, the combination with a heating chamber, and a steam boiler, of a superheating steam pipe leading from the boiler and adapted to conduct steam from the boiler to the whistle, and a condenser connected with the boiler, substantially as set forth.

2. In a whistle, the combination with a heating chamber, and a steam boiler, of a superheating steam pipe leading from the boiler and adapted to conduct steam from the boiler to the whistle, a water tank, and a condensing pipe extending from the tank to the boiler, substantially as set forth.

3. In a whistle, the combination with a heating chamber, and a boiler, of a superheating steam pipe leading from the boiler and adapted to conduct steam from the boiler to the whistle, a water tank, a pipe extending from the tank to the boiler, and an air pump for creating a pressure of air in the tank, substantially as set forth.

4. The combination in a steam generator, a pipe leading therefrom and terminating in a whistle, an air tight cold water tank having an air space above the water, a water pipe leading from the tank below the water level and opening into the generator, and means to create an air-pressure in the water tank approximately equal to the maximum pressure allowable in the generator, whereby if said pressure is exceeded the water is driven back from the generator into the cold water tank.

5. The combination of a steam whistle, a steam generator or boiler, a pipe connecting

the generator or boiler with the whistle, a water reservoir in constant free communication with the generator or boiler, and means to cause the water to freely circulate between the reservoir and boiler in both directions under elastic pressure.

6. The combination of a steam whistle, a steam generator or boiler, a pipe connecting the generator or boiler with the whistle, a water reservoir in constant free communication with the generator or boiler, and means to cause the cold water to freely circulate between the reservoir and boiler in both directions under maintained air pressure.

7. The combination of a steam whistle, a steam generator or boiler, a pipe connecting the generator or boiler with the whistle, a water tank, means to force the water into the boiler or generator under pressure, and a communication between the tank and generator or boiler to permit the free flow of the hot water and steam backward toward the tank in case of an excessive pressure of steam.

8. The combination of a steam whistle, a steam generator or boiler, a pipe connecting the generator or boiler with the whistle, a water reservoir in constant free communication with the generator or boiler, means to cause the water to freely circulate between the reservoir and boiler in both directions under elastic pressure, and a condenser to condense the steam which may be forced back from the boiler or generator.

9. The herein described method of maintaining a continued pressure of steam for operating a steam whistle at intervals of time which consists in supplying a boiler upon which a steam whistle is arranged with water under an elastic pressure with freedom of circulation into and out of the boiler in accordance with the pressure contained therein, and condensing the steam forced backward from the boiler toward the water supply when the pressure within the boiler becomes abnormally high, whereby a supply of water is delivered to the boiler automatically in quantities just sufficient to supply the requirement of the steam whistle.

In testimony whereof I have signed this specification in the presence of two subscribing witnesses.

FRANK. W. OFELDT.
